UNITED STATES PATENT OFFICE.

J. DUDLEY RICHARDS, OF BOSTON, MASSACHUSETTS.

PICTURE-EXHIBITING EASEL.

SPECIFICATION forming part of Letters Patent No. 310,319, dated January 6, 1885.

Application filed December 31, 1883. (No model.)

To all whom it may concern:

Be it known that I, J. DUDLEY RICHARDS, of Boston, county of Suffolk, State of Massachusetts, have invented an Improvement in 5 Picture-Exhibiting Easels, of which the following description, in connection with the accompanying drawings, is a specification, like letters on the drawings representing like parts.

My invention has for its object the production of an easel especially adapted for the exhibition of pictures, the easel having a number of parts which by change of position enables one part after another to be utilized according to the desire of the party using the 15 same, and the size of the pictures to be exhibited.

My invention consists in an easel, substantially as hereinafter described, and specified in the claims.

20 Figure 1, in side elevation, represents in full lines one of my improved easels fully extended, the dotted lines showing the easel closed or shut up, and Fig. 2 is an elevation of Fig. 1, looking at it from the right, but 25 with the parts folded up.

As herein shown, the main part of the easel is composed of suitable side pieces, A B C, connected in pairs, the pieces A being extended upward and inclined forward from a base, 30 D, and being connected at or near the middle of their length with the pieces B by braces E, the pieces C serving as braces for the pieces A. The pieces B and C have their lower ends connected with the base D. The 35 pieces A B C, comprising one side of the main part of the easel so far described, are joined in pairs with like pieces at the opposite side thereof by the shelf G, which resembles a chair-seat, and by the base D, and 40 at their upper ends the pieces A are connected by the cross-piece H. The part G and cross-piece H serve to support a narrow bar, a, having an attached guide-loop, a', and a clamp, a'', composed of two arms, 2, pivoted thereon, 45 and holding between them a roller, 3, preferably of india-rubber. An adjustable picture holder, a'', having a hook or other suitable engaging device, 4, is passed down through the clamp a'', while the latter is elevated or its 50 arms 2 are substantially at right angles to the bar a, and thence through the guide-loop a', and with the clamp so held the holder a'' may

be readily raised or lowered to adapt the position of the hook 4 to the top of the picture b, Fig. 1, the lower end of which rests on the 55 bracket b', then turned down, as in full lines, the said bracket being composed of two arms suitably connected together and pivoted at 5, so as to be turned up, as in dotted lines, Fig. 1, when not in use. The holder a'' having been raised to substantially the point where it is to be retained, the clamp a' is permitted to drop and the holder is permitted to settle between the roller 2 and the bar a, thus enabling the said clamp to act and retain the holder. The picture b, held as described, is inclined forward at its top, just as if it were hung upon a wall, whereas in all other easels known to me, if the top of the picture is firmly attached to the easel, the said 70 picture is always either upright or inclined backward at the top, thus presenting it to the light differently than when hung on the wall. Under the shelf or rest G is a foot, d, having a rest, d', connected therewith by hinges d''. Pictures with one edge on the shelf G will be 75 inclined to the right or backward viewing, Fig. 1, and rest against the pieces A. When the rest d' is turned up, as in full lines, it will aid in holding such pictures as are supported 80 on the table M, to be described, and when not to be used may be slid under the seat G and be held there in any suitable manner. Between the two sets of side pieces, A B C, below the seat G, is a table, M, it having its 85 base m, as herein shown, shouldered to slide on guides of the base D, (see Fig. 2,) and preferably this table will be provided with suitable rollers, as will also be the base D. The table M (shown drawn out in Fig. 1) has a 90 connected step, N, herein shown as pivoted to it at n', which may be made to occupy the full-line position, Fig. 1, to hold pictures, or be contained within the table, as shown by dotted lines, when not in use. The table M is 95 provided with a rest, o'', composed of a horizontal bar and two bars, o, fitted to slide in guides o'. With the parts as in full lines, Fig. 1, pictures standing on the top of the table M may be leaned against the rest d' or 100 against the rest o'', as desired, the said parts co-operating to form a portfolio-stand. The easel may be made of any desired size, height, width, or breadth, or of any desired material,

the pieces A B C being of any desired diameter or shape in cross-section, according to the fancy. The front of the easel is shown at the right of Fig. 1, and ordinarily it will contain 5 a picture, b, on the rest b², and a second picture, t, may stand on the part t' of base D, thus practically concealing the easel. Without disturbing the said pictures b t, the easel may be reversed or turned half-way around, 10 and other pictures may be successively placed upon the shelf G, table M, and step N, and exhibited as long as desired.

I claim—

1. In an easel, the supporting-frame provided with the forwardly-inclined pieces A, the bar a, arranged between the pieces A and substantially parallel therewith, combined with a loose picture-holding bar provided with a picture-engaging device, a clamp-plate secured in fixed position on the bar a, and having a clamp pivoted thereto, adapted to be pivotally moved over the face of the bar a, and to automatically bite and retain the picture-holding bar in desired position on said bar a, 25 and a rest to support the lower edge of the picture and enable the upper end to be tipped forward, substantially as set forth.
2. In an easel, the bar a, provided with a fixed clamp-plate having a clamp pivoted thereto, and adapted to be pivotally moved over the face of the said bar, as specified, combined with an independent bar or picture-holder having a picture-engaging device, and adapted to be passed between the clamp and the face 35 of the bar a, so as to be automatically retained on said bar, substantially as described.
3. In an easel, the bar a, provided with a retaining-loop, and a fixed clamp-plate having a clamp pivoted thereto, and adapted to be pivotally moved over the face of the said bar, as 40

specified, combined with an independent bar or picture-holder having a picture-engaging device, and adapted to be passed between the clamp and the face of the bar a, so as to be automatically retained on said bar, substantially as described.

4. The main part of the easel, composed of the connected side pieces and the seat G, combined with the sliding table M, substantially as described.

5. The connected side pieces of the easel and means to hold a picture inclined forwardly, combined with a horizontally-sliding table, M, and rest o², constituting a portfolio-stand, substantially as described.

6. The main part of the easel, composed of the connected side pieces, and the seat G, and the sliding table M, combined with the rest d', substantially as described.

7. The main part of the easel, composed of the connected side pieces and the seat G, the sliding table M, and the rest d', combined with the slide and bar o², substantially as set forth.

8. The main part of the easel, composed of the parts A B C, and the seat G, and the sliding table M, and the rest d', and the slide o² and bar o², combined with the step N, substantially as shown and described.

9. The herein-described easel, composed of the main parts A B C G and base D, a sliding table, M, rests d' and b², and slide and bar o², all substantially as described.

In testimony whereof I have signed my name to this specification in the presence of two subscribing witnesses.

J. DUDLEY RICHARDS.
